United States Patent Office.

WILLIAM E. CLARKE, OF TROY, NEW YORK, ASSIGNOR TO MARY E. DEAN,
OF SAME PLACE.

Letters Patent No. 105,908, dated August 2, 1870.

IMPROVEMENT IN JOINT FOR TONGS, &c.

The Schedule referred to in these Letters Patent and making part of the same.

To all whom it may concern:

Be it known that I, WILLIAM E. CLARKE, of Troy, in the county of Rensselaer and State of New York, have invented a new improved Joint for Tongs, &c.; and I do hereby declare that the following is a full, clear, and exact description thereof, which will enable others skilled in the art to make and use the same, reference being had to the accompanying drawing forming part of this specification, in which—

Figure 1 represents a side view, partly in section, of my improved joint, showing it on the tongs.

Figure 2 is a transverse section of the same.

Figure 3 is a face view of one plate of the joint.

Similar letters of reference indicate corresponding parts.

This invention relates to a new joint for ice-tongs and other tongs, and similar purposes, being particularly adapted to tongs made of wire, although it may also be used on articles made of different material.

The invention consists chiefly in making the joint of two plates, which are pivoted together, and which are so shaped as to receive and conceal the shanks of the tongs, as hereinafter more fully described.

A A, in the drawing, are the two shanks or handles of the tongs.

B B are the two plates which constitute the joint.

These plates are of circular form, and are connected by a screw-bolt or pin, C, which passes through their centers, as shown.

Each plate has a depression or recess, a, in its inner face, for receiving one of the shanks, the said shanks being bent, to clear the pin C, as shown in fig. 1.

The recess a in each plate B is concealed by a surrounding flange, b, so as not to be perceptible from the outer side.

The recess is in one half only of each plate B. The other half, c, is left solid, as shown in fig. 2.

A prong, d, projects from the solid half c of each plate B, into the recess on the opposite plate, and serves, as it fits against the inner face of the flange b, to steady and guide the plates during their motion on the pivot.

Each shank A is, by this arrangement, secured in its plate B, so that it cannot turn in, but only with said plate, and a swivel joint is thus produced, which will operate without much friction, and perfectly steady.

One great advantage of this joint is that it permits the use of the wire shanks in their simplest form.

Having thus described my invention,

I claim as new and desire to secure by Letters Patent—

1. The swivel point, consisting of the plates B B and pin C, each plate having a recess on one side, for the reception of one tong-shank, as set forth.

2. The wire tongs, arranged in combination with a swivel point, consisting of circular plates B, in the manner described.

WM. E. CLARKE.
